INDOOR ANTENNA FOR BOTH ULTRA HIGH AND VERY HIGH FREQUENCY RADIO WAVES

Robert L. Larson, Auburn, Mass., assignor to Parker Metal Goods Company, Worcester, Mass., a corporation of Massachusetts

Filed Aug. 10, 1964, Ser. No. 81,223

Term of patent 14 years

(Cl. D26—14)

FIG. 1 is a front elevational view of an indoor antenna for both ultra high and very high frequency radio waves, showing my new design; and

FIG. 2 is a right side elevational view, the opposite side being substantially a mirror image thereof.

I claim:

The ornamental design for an indoor antenna for both ultra high and very high frequency radio waves, as shown and described.
